UNITED STATES PATENT OFFICE

HARRY NAGIN, OF PITTSBURGH, PENNSYLVANIA, ASSIGNOR TO TRI-LOK COMPANY,
OF PITTSBURGH, PENNSYLVANIA, A CORPORATION OF PENNSYLVANIA

GRATING EDGE STRUCTURE

Application filed June 27, 1927. Serial No. 201,703.

This invention relates to grating edge structures and particularly to an edge structure for gratings employing girder bars and cross bars.

5 A grating of this character is described and claimed in my Patent No. 1,631,691, June 7, 1927. The invention is herein described as particularly applied to such grating structure, but it will be understood that it has 10 numerous other applications.

Those gratings which employ girder bars and cross bars depend upon some form of joint between the bars to hold the grating together as distinguished from gratings employing corrugated members which lie between the girder bars and are riveted thereto. In the cross bar type of grating it has heretofore been necessary to extend the cross bars a short distance beyond the girder bar at the 20 edge of the grating in order to insure a proper joint. Where this construction was undesirable, it was necessary to weld the outside girder bar to the cross bars or else to resort to riveting between the girder bar and the 25 cross bars.

I provide a grating whose cross bars have projecting end portions, these projecting portions being so bent as to engage the girder bar and prevent displacement thereof. Preferably, the projecting cross bar portion is bent 30 into general parallelism with the girder bar and in contact therewith.

The type of grating disclosed in my prior patent comprises girder bars having curved 35 slots therein and straight cross bars forced into the slots so as to form locking tongues which permanently secure the parts together. Where this type of grating is used there is a particularly strong joint secured at the edge 40 girder bar. At the same time, the joint is not open to the objection that sharp ends of cross bars project.

In the accompanying drawings illustrating the present preferred embodiment of my 45 invention and one modification thereof, Figure 1 is a top plan view partly broken away showing my invention applied thereto;

Figure 2 is a side elevation of Fig. 1; and

50 Figure 3 is a view similar to Fig. 2 but showing a modified construction.

Referring first to Figures 1 and 2, there is shown a grating comprising girder bars 2 and cross bars 3. The girder bars have slots formed therein, these slots having an upper straight portion 5 and a lower curved portion 55 5^a. The cross bars 3 are generally flat but during the process of manufacture they are forced into the slots and portions thereof are permanently deformed into locking tongues 6 60 which secure the parts together. 60

The cross bars 3 have portions 4 which lie outside the edge girder bars 2^a. The portions 4 are bent at an angle to the body of the cross bars so as to lie in general parallelism and in contact with the edge girder bars 2^a. The 65 end portions are bent around before the cross bars are forced into the slots. The bend is at the joint between the cross bar and the girder bar and is on a line substantially perpendicular to the plane of the grating surface. By reason of the fact that a locking tongue 6^a is formed adjacent each end portion 4 during the assembling of the grating, the metal is bent to such shape that a particularly strong corner is secured. 70 75

Figure 2 shows the end portions 4 bent in such direction that the locking tongue is directed toward the body of the portion 4. Figure 3 shows a modified grating wherein the locking tongues are directed away from 80 the body of the portions 4^a. Either form of joint is very strong and is effective for holding the edge girder bar firmly in place. The structure is very solid and has no tendency 85 to rattle or work loose.

It is generally desirable to use either the joint of Figure 2 on both edges of the grating or the joint of Figure 3 on both edges thereof. It will be understood therefore that the portions 4 may be directed the same way on 90 opposite edges of the grating or in opposite ways depending on whether there is an odd or even number of girder bars in the grating.

I have illustrated and described preferred 95 forms of my invention as applied to a grating constructed according to my prior patent. It will be understood, however, that the invention is not limited to the forms shown as it may be otherwise embodied within the scope 100 of the following claim.

I claim:

The method of making a grating which comprises forming a curved slot in a girder bar, providing a cross bar of different cross sectional shape than the slot in the girder bar, and having an end portion extending at substantially right angles to the cross bar proper, placing the cross bar in such position relative to the girder bar that the end portion of the cross bar lies adjacent the plane of a side face of the girder bar, and forcing the cross bar into the slot whereby the end portion of the cross bar lies adjacent the girder bar, and that portion of the cross bar proper adjacent the bent over portion is permanently deformed by being forced into the slot.

In testimony whereof I have hereunto set my hand.

20

HARRY NAGIN.
